Max Freeman, New York, N. Y.

Application May 17, 1947, Serial No. 139,117

Term of patent 3½ years

(Cl. D45—19)

To all whom it may concern:

Be it known that I, Max Freeman, a citizen of the United States, residing at New York, in the county of New York and State of New York, have invented a new, original, and ornamental Design for a Pin or the like, of which the following is a specification, reference being had to the accompanying drawing, forming a part thereof.

In the drawing:

Fig. 1 is a front elevational view of a pin or the like;

Fig. 2 is a rear elevational view; and

Fig. 3 is an end elevational view of the same.

I claim:

The ornamental design for a pin or the like, as shown.

MAX FREEMAN.
